ENVELOPE MACHINE

Abraham Novick, Flushing, N. Y., assignor to F. L. Smithe Machine Co. Inc., New York, N. Y., a corporation of New York

Application April 28, 1932, Serial No. 607,918

20 Claims. (Cl. 93—61)

This invention relates to envelope making and more particularly to the making of window envelopes or other envelopes having lining patches incorporated in them.

It is an object of the invention to provide, in combination, novel and efficient means for advancing a patch web, for gumming end portions thereof, for severing the individual patches, and for applying the patches accurately to the envelope blanks.

It is a feature of the invention that the successive patches are applied to the successive envelope blanks of a stack, the patch in each instance being applied to an end blank of the stack before the position of the blank has been in any way disturbed by the separating and feeding mechanism. This assures that the gummed patch will be deposited on a blank, and it also assures the accurate application of the patch.

It is a further object of the invention to contrive novel and effective means for withdrawing the envelope blanks individually from the stack.

It is a further object of the invention to provide in combination with means for advancing the blanks singly in spaced out relation after they have had the patches applied to them, a mechanism for rearranging the blanks in fanned-out or shingled relation preliminary to the gumming of the sealing flaps, without the necessity for first restacking the blanks.

In accordance with a broad aspect of certain features, the invention comprehends the heating of the border portions of patches which are adapted to be rendered tacky by such heating. Other features relate to the practicing of the invention in the manner just specifically referred to.

Other objects and advantages will hereinafter appear.

In the drawings forming part of this specification,

Figure 1 is a fragmentary, diagrammatic side elevation of an envelope machine of the wide range open side type, having features of the present invention embodied therein;

Figure 2 is a diagrammatic view illustrating the application of gum to the sealing flaps of the envelope blanks;

Figure 3 is a fragmentary, sectional view taken on the line 3—3 of Figure 4, looking in the direction of the arrows;

Figure 4 is a fragmentary, sectional view taken on the line 4—4 of Figure 3, looking in the direction of the arrows;

Figure 5 is a fragmentary, vertical, sectional view taken through the patch applying drum and mechanism associated therewith, the section being taken on the line 5—5 of Figure 7, looking in the direction of the arrows;

Figure 6 is a fragmentary, vertical, sectional view of a pneumatic blank feeder and associated parts;

Figure 7 is a detail, sectional view taken on the line 7—7 of Figure 5, looking in the direction of the arrows;

Figure 8 is a detail, sectional view taken on the line 8—8 of Figure 5, looking in the direction of the arrows;

Figure 9 is a detail, sectional view, partly broken away, the section being taken on the line 9—9 of Figure 5, looking in the direction of the arrows;

Figure 10 is a detail, sectional view, the section being taken on the line 10—10 of Figure 6, looking in the direction of the arrows;

Figure 11 is a detail view in side elevation of a portion of the mechanism for driving the patch applying drum, the mechanism being illustrated as viewed from the right in Figure 4;

Figure 12 is a fragmentary, detail view in side elevation of the intermittent driving mechanism for the patch drum, the mechanism being also illustrated as viewed from the right in Figure 4;

Figure 13 is a fragmentary, sectional view generally similar to Figure 5 but illustrating a modified form of mechanism;

Figure 14 is a view in side elevation taken at the line 14—14 of Figure 13, looking in the direction of the arrows;

Figure 15 is a sectional view taken on the line 15—15 of Figure 13, looking in the direction of the arrows;

Figure 16 is a sectional view on a larger scale than Figure 15, illustrating a detail of the structure of Figure 15;

Figure 17 is a fragmentary, detail, sectional view taken on the line 17—17 of Figure 15, looking in the direction of the arrows;

Figure 18 is a fragmentary, sectional view, taken on the line 18—18 of Figure 15, looking in the direction of the arrows;

Figure 19 is a fragmentary, detail view in perspective, illustrative of a feature of the patch drum; and

Figure 20 is a diagrammatic view illustrating the way in which the heating means is arranged in the patch drum.

In order that a comprehensive idea of the mechanism illustratively embodied in the draw-

ings may be had, the principal parts will first be briefly described in a general way without attention to detail.

5 The envelope blanks B are provided in a stack 1 held by a magazine which includes upstanding bars 1a and stack supporting means like that disclosed in my Patent No. 1,807,864, dated June 2, 1931, for maintaining the top of the stack at a substantially uniform level. The envelope 10 blanks are of the window type, each blank having a window opening cut in it. A patch web 2 is fed from a reel 3 around suitable guide and take-up devices to a polygonal drum 4. The drum is illustrated as hexagonal and is rotated intermittently 15 or step by step, each step being 60° in extent. The patch web is fed to the upper side of the drum and is held to the drum by suction. While the drum is stationary a gum applying device comes down upon the web on the upper side of 20 the drum to gum a portion of the web which by severance will subsequently become the marginal portion of a window patch. After the gum has been applied to a patch portion of the web, that portion is advanced through two feeding steps 25 and then severed from the web end. Still held to the drum by suction, the severed patch is advanced with the drum through another feeding step to the lower side of the drum.

Between successive rotary feeding steps of the 30 drum, the drum is bodily reciprocated. The downward bodily movement of the drum carries the gummed patch at the lower side of the drum down against the upper face of the uppermost envelope blank of the stack. While the drum 35 bears against the stack the suction is cut off from the stack engaging face of the drum so that the blank is not drawn upward by the drum and there is no tendency to detach the patch which has just been applied.

40 While the drum bears against the stack and clamps the blanks against movement, an intermittently operated blower or flutterer 5 blows air against the upper leading corner of the stack to raise the uppermost blank into contact with a 45 pneumatic feeding device 6. The feeding device 6 projects through a guide plate 7 and has numerous openings in its periphery. Only those openings which are exposed below the guide plate 7 are in communication with the source of suction, however. The feeding device 6 cannot advance the top blank until the drum has moved upward sufficiently to release it, but it does hold the leading margin of the top blank up against itself after the blower has been cut off to permit 50 the underlying blanks to drop back to their original positions within the confines of the magazine guides. As soon as the drum 4 moves upward far enough to unclamp the top blank the device 6 advances the top blank only to a feeding 55 couple comprising co-acting rolls 8 and 9. Thus the timing of the blanks is controlled by the drum.

The rolls 8 and 9 deliver the blanks in spaced out relation to a conveyor 10 comprising opposed 60 belts 11 and 12. The conveyor 10 is arranged to conduct the blanks through a wide sweeping arc so as to avoid possible loosening of the patches from the blanks B. The conveyor 10 inverts the blanks and delivers them onto a relatively slow moving conveyor 13, the blanks being re-arranged in fanned-out relation for delivery to a fan-out gumming device 14 and thence to a fan-out drier 15 like the one shown in my Patent No. 1,807,862, of June 2, 1931. The drier 15 delivers the blanks to other instrumentalities, not illustrated, which

complete the manufacture of the blanks into envelopes in the usual manner.

Referring now more particularly to Figure 3, the patch web 2 is drawn from the reel 3 around a guide roller 16 by feed rolls 17 and 18. The patch web passes thence around a fixed, idler guide roll 19 and a movable roll 20. The latter roll is carried by arms 21 secured to a shaft 22 and is urged against an abutment screw 23 by a spring 24, the spring being connected at one end 10 to the tail portion of one of the arms, and at the other end to a fixed part of the machine frame. The abutment screw 23 is threaded in a fixed part 15 of the machine frame. The roller 20 is obviously adapted to take up slack in the web between 20 the feeding couple 17, 18 and the drum 4. The spring 24 is light enough, however, to permit the roller 20 to be readily drawn forward by the drum when necessary so that liability of dislodging the web relative to the drum is avoided. From the 20 roller 20 the patch web passes onto the uppermost face of the drum 4. The drum 4 is fixed upon a shaft 26, which shaft is journaled in a pair of arms 27. The arms 27 are fast upon a rock shaft 28. One of the arms 27 includes an upstanding 25 ear or finger 29 which is connected through a link 30 with one arm of a rocking lever 31 which is journaled on a fixed shaft 32. The opposite end of the lever 31 includes an ear 33 which is impaled upon a rod 34. The ear is held against the 30 lower face of a nut 35, threaded on the rod 34, by means of a spring 36 which surrounds the lower end of the rod and abuts against a nut 37 threaded onto the rod. The upper end of the rod 34 is pivotally connected to one end of a lever 38 35 journaled on a shaft 39. The opposite end of the lever 38 carries a cam follower 40 which runs in a groove 41 of a track cam 42. The track cam is mounted upon a shaft 43 and is driven by such shaft. The cam 42 is effective through the train 40 of mechanism described to reciprocate the drum 4 about the axis of shaft 28, there being one reciprocation between successive rotational steps of the drum.

Provision is made of a gummer 44 and of 45 means for reciprocating the gummer to carry it back and forth between a gum receiving position and a gum applying position. The gummer comprises a gum applying foot or pad 45 and arms 46 carrying such foot. In the gum applying position the foot bears against the upper face of the drum 4 with the drum in its elevated position, as illustrated in Figure 3. The cam shaft 43 carries a cam having a cam track for cooperating with a cam follower 47 carried by a rocking lever 48 to 50 move about the axis of a shaft 49. The rocking lever is connected through a link 50 with a crank 51 fast on a shaft 52. The arms 46 of the gummer are also fast upon shaft 52 and are oscillated by the motion imparted to the cam follower 47, 60 in timed relation to the movement of the drum.

Gum is applied to the gummer foot 45 in its uppermost position, illustrated in dot and dash lines in Figure 3, the gummer foot being caused to remain stationary in this position to receive 65 gum from a transfer roll 53 and to correlate its movements with the movements of the roll 53 and the operating mechanism for such roll. The roll 53 is rotatably mounted upon slides 54 which are reciprocably mounted upon parallel guide 70 rods 55. The guide rods 55 are carried, at their lower ends, upon supporting rods 56 which in turn are held to ears 57 of a bracket 58 which is fixed by means of a set screw 59 upon a cross bar 60 that forms a fixed part of the machine 75

frame. Each supporting rod 56 passes through one of the ears 51 and nuts 61 and 62 threaded upon the rod 56 engage opposite sides of the ear to hold the rod in fixed position. The upper ends 5 of the rods 55 may be similarly supported.

A cam, fast upon cam shaft 43, co-acts with a cam follower 63 which is carried by a crank 64 fast on a shaft 65. Arms 66, also fast on the shaft 65, are connected at their lower ends through 10 links 67 with the slides 54. The cam is effective through the train of mechanism described to carry the cam transfer roll 53 back and forth between the lower position, illustrated in full lines in Figure 3, and an upper gum receiving 15 position, illustrated in dot and dash lines in Figure 3. In the latter position the transfer roll 53 lies in contact with a driven roller 68 that runs in a gum pot 69. When the gummer foot 49 first reaches its uppermost position as illustrated 20 in dot and dash lines in Figure 3, the transfer roll 53 is in its lowermost position. The transfer roll 53 is then moved upward against the roller 68 and is returned to its lowermost position. In the course of the latter movement the transfer 25 roll runs across the face of the gummer foot 45 and applies gum thereto. After this the gummer foot is lowered to the full line position of Figure 3 and is again retracted.

The gummer section of the patch web is not 30 immediately severed from the end of the patch web but remains attached to the web and held to the drum for two feeding steps of the drum after the gum has been applied. When it reaches the rotative position marked c (Figure 3), however, 35 a severing mechanism is operated to cut the end section off of the web. The severing mechanism comprises a knife 70 carried by a bracket 71 upon the outer end of arms 72. The arms 72a are rockingly mounted by shaft 73 to which is secured an upwardly extending arm 73a having a follower 74 which cooperates with a cam on the cam shaft 43 for moving the knife 70 to sever the web at a time when the drum 4 stands stationary in the position illustrated in full lines in Figure 3. The knife, in cutting the web, moves into a groove 75, there being one such groove along each edge of the drum, and co-acts with an edge of one of the six perforated plates 76 which cover the respective faces of the drum.

50 As has been indicated, the patch web and the severed patches are held to the drum by suction. It has also been stated that the drum is not only reciprocated in the manner already described, but that it is intermittently rotated through steps of 55 60°. The mechanism for controlling communication of the several drum sections with a source of suction and for imparting intermittent rotation to the drum is more particularly illustrated in Figures 4, 5, 7, 8, 9, 11 and 12. The mechanism for imparting intermittent rotation to the drum will first be described, reference being particularly had to Figures 4, 5, 11 and 12. As has been stated, the drum is fast upon a shaft 26, which shaft is reciprocated bodily by the oscillation of the arms 27 in which it is carried. The shaft 26 is connected through a universal joint 77 with a shaft 18 by which it is driven. Mechanism is provided for imparting the desired step by step rotation to the shaft 18 while permitting the shaft 18 to be tilted and to shift longitudinally to accommodate itself to the bodily movements of the shaft 26.

A shaft 18 may be regarded as the prime mover with reference to the mechanism for driving shaft 5 26, involved in the present description. The

shaft 19 has fast upon it a worm 80 provided with parallel ribs 81 which define between them a worm groove 82. The worm groove thus defined extends substantially helically for about 180° and substantially circumferentially for another 180°. A disc 83 carries six equally spaced rollers 84 near its periphery which are adapted to be engaged and advanced successively in the cam groove. With the cam groove designed as described, the disc 83 is alternately rotated and 10 locked against rotation. The disc 83 is fixed upon a shaft 85 which is journaled in a bearing 86 provided in a fixed frame member 87. The disc 83 has riveted to it a pinion 88 which meshes with a pinion 89 and drives the latter. The pinion 15 89 is secured by rivets 89a upon a ring member 90 which is fast upon a hollow shaft 91. The shaft 91 is journaled in a bearing 92 provided in the fixed frame member 87. The shaft 78 extends through the hollow shaft 91 and the bore of the 20 hollow shaft is desirably made conical to accommodate tilting of the shaft 78. The shaft 78 is universally connected to the ring member 90, as best illustrated in Figures 9 and 11. The ring member 90 is provided with diametrically opposed, radially extending pivot bolts 93 which pivotally support the inner ring member 94. The inner ring member 94 is in turn provided with diametrically opposed, radially extending pivot bolts 95 which extend at right angles to 30 pivot bolts 93 and which pivotally support a hub or sleeve member 96. The hub member 96, as best seen in Figure 4, carries keys 97 which interfit with grooves 98 in the end of the shaft 78. The shaft 78 is adapted to be driven from the hub 35 member 96 through the keys 97 but is longitudinally slid able relative to the hub member 96. It is during the period when the disc 83 and hence the drum 4 is locked against rotation that the drum is moved from its uppermost position down 40 against the stack and returned to its uppermost position.

The mechanism for effecting connection and disconnection of the drum sections with a source of suction at appropriate times is best illustrated 45 in Figures 4, 5, 7, 8 and 9. A conduit or bore 99 extending through a fixed frame member 100 communicates with a suitable source of suction and terminates in a horizontally extending passage 101, which in turn communicates with an 50 arcuate groove 102 in a face of the frame member 100. (See particularly Figures 5 and 7.) A rotary distributor 103 runs against the face of the frame member 100. The distributor 103 is mounted upon a shaft 104, the shaft being 55 journaled in the frame member 100 and having fast thereon a pinion 105 which is driven continuously by a pinion 106. The shaft 104 is constantly rotating and makes one revolution for each revolution of the shaft 26 by which the drum is 60 carried, but since the shaft 26 is intermittently operated there is at times a gain and at other times a corresponding loss of rotary movement as between the shafts 104 and 26. It will be remembered also that the shaft 26 moves bodily 65 with relation to the shaft 104. The distributor 103 is left free to move longitudinally upon the shaft 104 so that it may maintain a snug engagement at all times with the face of the frame member 100 and thus automatically avoid leakage 70 due to wear. To this end, provision is made at the opposite side of the distributor from the frame 100 of a collar 107 fast on the shaft 104. The collar is provided with driving pins 108 which extend into openings 109 in the distributor for 75

rotating the distributor in unison with the shaft 104. The collar 107 also has springs 110 set into recesses thereof for thrusting the distributor into firm engagement with the face of the frame member 100. The distributor, as shown in Figures 5 and 7, includes six passages 111 disposed at equal intervals and equidistantly from the center of the distributor. Each of these passages extends at one end through a face of the distributor in a position adapting it for communication with the groove 102. Each passage at its opposite end lets out through the periphery of the distributor and communicates with a flexible hose 112. The hoses 112 are connected at their opposite ends with passages 113 formed through a collar 114 fast on shaft 26. The hoses are long and flexible enough to accommodate the relative rotary and bodily movements of the distributor and the shaft 26. Each of the passages 113 through the collar 114 communicates respectively with one of six passages 115, which passages extend longitudinally through the shaft 26. (See particularly Figures 5, 8 and 9.) Each of the passages 115 communicates at its opposite end with passage 116 which extends radially outward through the body portion 117 of the drum 4 into a suction chamber 118. There is one of these suction chambers beneath each face of the drum, each suction chamber being formed by providing a recess in a face of the drum and covering the same with the perforated plate 76 which is secured to the drum by means of screws 120 threaded into bosses 121. It will be seen that each suction chamber of the drum is always in communication with a particular one of the passages 111 of the distributor. So long as the associated distributor passage is in communication with the passage 99 of the frame member 100 suction will be applied to the suction chamber. The groove 102 is so designed that suction is first applied to a suction chamber 118 when it is in its uppermost position, that is, in the position marked *a* in Figure 3.

The chamber remains in communication with the source of suction through positions *b* and *c* and until after it has arrived at position *d*. The drum, held against rotation, is then depressed into engagement with the top envelope blank of the stack whereupon the chamber 118, whose cover wall 76 bears against the stack, is cut off from communication with the source of suction and placed in communication with the atmosphere by the continued rotation of the distributor. This result is secured by the rotation of the passage 111 under consideration beyond the end of the groove 102 and into communication with a short groove 122 (Figures 5 and 7) which is formed in the frame member 100 and which communicates through a passage 123 with the atmosphere. During rotation of the chamber through positions *e* and *f* the suction is not re-admitted to the chamber 118.

As soon as the drum 4 has applied a patch and has moved upward, the blower 5 is effective to raise the uppermost blank into engagement with the pneumatic feeder 6. The pneumatic feeder comprises a shaft 124 having fast on one end a pinion 125 which is constantly driven by a meshing pinion 126. The shaft is journaled in bearings 127 and 128 which are supported in a sleeve 129 carried by a hub 130 on the fixed frame member 81. Two feeding discs 131 and 132 are fixed on the shaft 124 at the opposite end of the shaft from the gear 125. These feeding discs are spaced from one another and a chamber element

133, which may be a casing, is mounted on the shaft between them. The casing 133 is fixed against rotation, being held fast to a tube 134 by a set screw 135. The tube 134 is clamped in a bracket 136 which is non-rotatably mounted upon the sleeve 129. A hose 137 which communicates with a source of suction is connected to one end of the tube 134 and communicates through the tube with a chamber or passage 138 in the casing 133. The chamber 138 is provided with a lateral passage 139 which extends in opposite directions to the faces of the feeding discs 131 and 132. Each of the discs is provided with a multiplicity of concentrically arranged lateral passages 141 adapted to be brought successively into register with the lateral passage 139 of the casing 138. Each of the lateral passages 141 communicates with a radial passage 142 which extends outward through the periphery of the disc.

It will be evident upon comparison of Figures 6 and 10 that each passage 141 is placed in communication with the passage 139 at about the time when the associated radial passage 142 has its open end fully exposed through the guide plate 7, and that the passage 141 moves out of register with the passage 139 at about the time when the open end of the associated radial passage 142 begins to recede behind the guide plate 7. Thus each radial passage 142 is made effective to hold an envelope blank to itself by suction when it is exposed below the guide plate, but suction is not applied to it at other times. It will be understood that the next succeeding passage 142 becomes effective before the preceding one is ineffective.

The pneumatic feeder advances the uppermost blank to the feed rolls 8 and 9. (Figures 1, 3 and 4.) The rolls 9 are fixed upon a driven shaft 143 and the rolls 8 are fixed upon a shaft 144 carried by arms 145 which are secured upon the cross bar 60. The rolls 8 and 9 are disposed outside the lateral bounds of the zone in which the window patches travel so that there is no tendency to squeeze out the freshly applied adhesive. The movement of the drum 4 controls the timing of the delivery of the blanks to the rolls 8 and 9 so that the blanks are delivered in evenly spaced relation to the drier 10.

As has been previously mentioned, the blanks travel through the drier 10 in spaced out relation, but they are re-arranged in fanned-out shingled relation as they leave the drier. In order to avoid the liability of catching the patch of one blank against the trailing edge of a preceding blank when effecting this rearrangement of the blanks, the conveyors 11 and 12 of the drier 10 are disposed to deliver the blanks in a plane somewhat above the plane of the receiving end of conveyor 13. The conveyor 13 travels slowly as compared with conveyors 11 and 12. An idler roll 146 bears against the upper stretch of conveyor 13 and is carried at the end of an arm 147 which is pivotally mounted on a crank 148. A spring 149 draws the arm 147 downward and causes the roll 146 to bear against the envelope blanks on the conveyor with yielding pressure. The crank 148 is fast on a rock shaft 150 which is oscillated in timed relation to the arrival of the blanks. The roll 146 is free to be driven by the conveyor 13 or to roll upon it when moved relatively to it. The roll 146 is effective to preserve the timed relation of the blanks and prevent accidental disarrangement of them. This device is the same as that disclosed and claimed in my

United States Patent No. 1,808,706, granted June 2, 1931, for Feeding mechanism for envelopes and the like. The remainder of the mechanism is of well known construction and requires no detailed description.

It will be observed, however, that the arrangement of the mechanism which has been described, including particularly the stack, the drier 10, and the conveyor 13, is so arranged and organized that the blanks are continuously advanced and are presented to the gummer 14 with their inner surfaces turned outwardly, with the sealing flaps at the trailing ends and with a trailing margin exposed for gumming. Thus the blanks are arranged on the stack, inner face up for reception of the patches, and with their bottom edges turned in the direction to become the leading edges as the blanks are fed off the stack. They are inverted by the drier and, since each blank falls a little behind its predecessor on the conveyor 13 when the blanks are arranged in fanned out relation, the lower trailing margins of the blanks are exposed, that is to say, the trailing margins of the inner faces of the blanks are exposed. The blanks in passing around the conveyor 13 are again inverted to turn these trailing exposed margins outward for contact with the brush member of gummer 14.

In Figures 13 to 20, disclosure is made of a modified form of mechanism in which the use of adhesive may be dispensed with, the drum being adapted to heat the marginal portions of the window patches to render them tacky so that they may be united with the window envelope blanks without the application of adhesive. The window patches may for this purpose be made of any suitable material adapted to be rendered tacky by heat, such as the material sold on the market as "cellophane."

In this embodiment a drum 4a is mounted upon a shaft 26a, which shaft is carried in arms 27a. The drum 4a is operated in the same manner as the drum 4 of the embodiment already described and its construction is generally similar. Communication of the several compartments 118a of the drum with the source of suction is controlled through a frame member 100a and a distributor 103a. The distributor passages are connected to passages which extend longitudinally of the shaft 26a through tubes 151, hoses 152 and tubes 153. The hoses 152 in this instance do not curve outward, the distributor being separated from the shaft 26a a sufficient distance to enable the hoses 152 to be disposed substantially in the direction of the length of the shaft 26a. The distributor is mounted upon and is driven by a shaft 104a, which shaft is rotated by a driven gear 105a. The shaft 104a has fast upon it an insulated plate 154 which carries metallic sockets 155 and 156.

The sockets 155 and 156 contain respectively compression springs 157 and 158 which press outwardly conductive plungers 159 and 160. The plunger 159 runs in engagement with a continuous inner metallic ring 161 while the plunger 160 runs in engagement with a continuous outer metallic ring 162. The rings 161 and 162 are both mounted in an insulated plate 163 and are provided respectively with conductive terminals 164 and 165. The opposite terminals of a source of electrical energy are connected respectively to the terminals 164 and 165 through conductors 166 and 167. The circuit is completed by connecting conductors 168 and 168a to the sockets 155 and 156 respectively and by connecting these conductors to the opposite ends of a heating element

168b disposed in the drum. It will be observed that in spite of the rotation of the conductor 168 relative to the conductors 166 and 167, the circuit is maintained continuously through the co-action of the rings 161 and 162 with the plunger pins 159 and 160. The conductors 168 and 168a extend axially through the shaft 104a, thence through an axial bore 169 of the shaft 26a, and thence outward through a passage 170 to be connected to the ends of the terminals of the heater element 168b near the periphery of the drum. The drum has recesses provided along its longitudinal edges and rabbets provided along its end edges. Channel members 171, of copper or of other suitable material of high heat conductivity, are set in the longitudinal recesses while channel members 172, also of copper or other suitable material of high heat conductivity, are set in the rabbets. The channel members 171 are cut away at their ends to afford communication with the channel members 172. The mouths of the channel members 172 are covered by dovetail bars 173 which are also of copper or like material, while channel members 174 of steel are secured in the mouths of the channel members 171. Passages are thus provided for reception of the heater element in the lower parts of the channel members 171 and 172, and the heat is conducted to the patch engaging faces of the drum through the highly conductive members. The perforated plates 16a are formed of any suitable material having a very low heat conductivity so that only the margins of the patches are heated. The disposition of the heater element in the drum is diagrammatically illustrated in Figure 20. In this figure it will be observed that the heater element passes first longitudinally across the drum through one of the channel members 171, then circumferentially through one of the channel members 172, then back across the drum through a second channel member 171, again circumferentially, and so on, until it has made the complete circuit of the drum. At this point, however, only half of the circumferentially extending channel members have received a length of the heater element and the heater element is led back in the same manner to make a complete circuit of the drum in the opposite direction. Thus arranged, two lengths of the heater element lie in each channel member 171 and one length of the heater element lies in each channel member 172. This arrangement is desirable, however, for the reason that members 174 are of channel form and of a metal such as steel to adapt them to coact with the patch cutter, so that the heat is less efficiently conducted to the longitudinal margins of the patches than to the end margins thereof where solid copper members are employed.

I have described what I believe to be the best embodiment of my invention. I do not wish, however, to be confined to the embodiment shown, but what I desire to cover by Letters Patent is set forth in the appended claims.

I claim:

1. An envelope machine comprising the elements combined and co-operating substantially as set forth in claim 4, and in which are provided a rotary suction feeder adjacent the top of the stack and a blower for lifting the top blank of the stack into engagement with the suction feeder.

2. In an envelope machine, in combination, means for supporting a stack of envelope blanks, a presser member, means periodically reciprocating

- ing the presser member into and out of engagement with the stack, a blank feeder comprising a guide limiting upward movement of a blank and a suction roll projecting downward 5 below the guide for a short distance to support the blank against the guide and advance it along the guide.
3. An envelope machine comprising the elements combined and co-operating as set forth 10 in claim 2, in which said suction roll is rotatable and has a multiplicity of peripherally open passages therein, and means for applying suction to said passages successively as they come below the guide and for cutting off the suction from the passages successively as they recede behind the 15 guide.
4. In an envelope machine, in combination, means for supporting a stack of blanks, a presser member, means periodically reciprocating the presser member into and out of engagement with the stack, and a slip drive blank feeder for withdrawing the top blank as soon as the presser releases it from the stack.
5. In an envelope machine, in combination, a magazine for supporting a stack of blanks, means periodically movable into and out of clamping relation to the stack, a suction feed roll, means operable while the stack is clamped to raise a margin of the top blank into engagement with 30 the suction feed roll but rendered ineffective before the stack is unclamped to permit such underlying blanks as may have been raised with the top blank to settle back to their original positions before the stack is unclamped.
- 35 6. In an envelope machine, in combination, a magazine for supporting a stack of blanks, a patch drum above the stack, means for rotating the drum step by step and for reciprocating it bodily into and out of engagement with the stack, 40 means for supplying a patch web to the drum and means cooperative with the drum to sever patches from the web.
7. In an envelope machine, in combination, a magazine for supporting a stack of blanks, a 45 patch drum above the stack, means for rotating the drum step by step and for reciprocating it bodily into and out of engagement with the stack, means for supplying a patch web to the drum and means cooperative with the drum to sever patches 50 from the web, said drum being divided into segments, and means for applying suction to each segment when it is in web receiving position and for cutting off the suction from the segment when it is in patch delivering position.
- 55 8. In an envelope machine, in combination, a magazine for supporting a stack of blanks, a patch drum above the stack, means for rotating the drum step by step and for reciprocating it bodily into and out of engagement with the 60 stack, means for supplying a patch web to the drum and means cooperative with the drum to sever patches from the web, and means movable against the drum to apply adhesive to the web.
- 65 9. In an envelope machine, a polygonal drum, means for advancing the drum step by step, means for supplying a web to the drum, and means cooperative with the drum to gum the web and thereafter to sever blanks from the web.
- 70 10. In an envelope machine, a polygonal suction drum, means for supplying a web to the drum, means to advance the drum step by step to bring the faces thereof to a series of stations, means to gum the web at a gumming station, means to sever the web at a severing station, and means to

cut off the suction from each face of the drum at a delivering station.

11. In an envelope machine, a polygonal suction drum, means for supplying a web to the drum, means to advance the drum step by step to bring the faces thereof successively to stations of a series, means to sever the web at a blank severing station, and means to cut off suction from each face of the drum at a blank delivering station. 5

12. In an envelope machine, means for supporting a stack of window envelope blanks, a polygonal suction drum, means for supplying a web to the drum, means to advance the drum step by step to bring the faces thereof to stations of a series, means to sever the web at a patch severing station, means to cut off suction from each face of the drum at a patch delivering station, means to depress the drum to apply the patch at the delivering station to the top blank of the stack, and means to remove the top blank from the stack after a patch has been applied to it. 10 15

13. In an envelope machine, means for supporting a stack of window envelope blanks, a polygonal suction drum, means for supplying a web to the drum, means to advance the drum step by step to bring the faces thereof to stations of a series, means to sever the web at a patch severing station, means to cut off suction from each face of the drum at a patch delivering station, 25 means to depress the drum to apply the patch at the delivering station to the top blank of the stack and means acting in timed relation to the drum for removing the blanks singly from the top of the stack. 30

14. In an envelope machine, in combination, means for supporting a stack of envelope blanks, a patch support, means for supplying patch material to the top of the patch support, means for gumming the patch material on the patch support, means for severing the gummed patch material to form a patch, means for inverting the patch support, and means for moving the inverted patch support vertically downward to apply the gummed patch at the bottom thereof to the top blank of the stack. 35 40 45

15. In an envelope machine, in combination, means for applying a patch to the top blank of a blank stack, means for removing each blank separately after a patch has been applied to it, means for rearranging the blanks in fanned-out relation and means for gumming the fanned-out blanks. 50

16. In an envelope machine, a patch carrier having a patch supporting face, heating means within the carrier, and highly conductive means for transmitting heat from the heating means to the marginal portions of the patch supporting face to concentrate the heat in such marginal portions. 55

17. The method of making window envelopes which comprises disposing envelope blanks in stack form, lining face up, applying patches to the lining faces of the blanks, each when it is at the top of the stack, removing the blanks individually, bottom edge first, as the patches are applied to them, inverting the blanks, rearranging the blanks in fanned-out relation and gumming the fanned-out blanks. 60 65

18. The method of making window envelopes which comprises applying window patches to successive envelope blanks at a patch applying station, conducting the blanks from the station in spaced-out relation, rearranging the blanks directly from spaced-out relation to fanned-out re- 70 75

lation, and gumming the sealing flaps of the fanned-out blanks.

19. In an envelope making machine, in combination, means for applying patches to successive envelope blanks at a patch applying station, a high speed feeding means for conducting the blanks from said station in spaced-out relation, a relatively low speed feeding means for receiving the blanks from the high speed feeding means and cooperating therewith to rearrange the blanks in fanned-out relation, and a fan-out gummer for gumming the sealing margins of the fanned-out blanks.

20. In a window envelope machine, in combination, a delivering conveyor, a receiving con-

veyor, said conveyors operating at different speeds such that the blanks are carried by one of the conveyors in spaced-out relation and by the other in overlapping relation, the successive blanks being relatively moved while in overlapping relation 5 during the transfer of the blanks from the delivering conveyor to the receiving conveyor, the delivering conveyor being disposed and arranged to deliver the blanks over the feeding plane of the receiving conveyor at the receiving end thereof, and spaced somewhat therefrom, whereby the overlapped areas of the blanks are held out of contact during relative movement thereof.
